DISCHARGE OUTLET ASSEMBLY FOR A HOPPER
George B. Dorey, Westmount, Quebec, Canada, assignor
to Enterprise Railway Equipment Company, Chicago,
Ill., a corporation of Illinois
Original application Dec. 30, 1958, Ser. No. 783,749, now
Patent No. 3,109,388, dated Nov. 5, 1963. Divided
and this application Oct. 30, 1963, Ser. No. 320,220
7 Claims. (Cl. 105—247)

This invention relates to an improved outlet assembly for a hopper and is particularly concerned with that type of outlet assembly having a sliding gate for the discharge opening of a railway hopper car and the like; this application is a divisional of U.S. application Serial No. 783,749, filed December 30, 1958, now U.S. Patent No. 3,109,388, dated November 5, 1963.

The objects of the invention, among others, are: To provide an outlet assembly having a sliding gate with outwardly and upwardly inclined side flanges adapted to underlie similarly inclined walls of the hopper structure; to provide an outlet assembly having a sliding gate wherein supports for the gate are localized adjacent each end thereof to insure sealing bearing contact at the leading end of the gate; to provide operating rack and pinion means for the gate located outwardly of the gate and frame; to provide toothed rack members at each side of the gate operable by geared pinions non-rotatably mounted on an operating shaft carried by the hopper; to provide toothed rack elements pivotally connected with a sliding gate so as to allow for deviation of the gate from the path of movement of the rack elements; and to provide an outlet frame structure having an upper section overlying hopper walls and a lower section in the form of a three-sided enclosure within which the upper section is nested and secured.

The invention further resides in details associated with the construction and in the manner in which various elements are coordinated to obtain the desired results and particularly in the novel means employed for guiding and supporting toothed rack elements.

For further comprehension of the invention reference may be had to the accompanying drawings wherein the invention is shown as applied to the hopper of a railway hopper car.

In said drawings FIGURE 1 shows the lower portion of one half the width of a railway hopper car with the improved outlet assembly applied thereto.

FIGURE 2 is a side elevational view of the structure shown in FIGURE 1 as viewed from left to right, the operating shaft being shown in section.

FIGURE 3 is a side elevational view of the structure shown in FIGURE 1 as viewed from right to left.

FIGURE 4 is a plan view of FIGURES 2 and 3 with the hopper walls eliminated to expose the frame proper and with certain parts broken away to better illustrate the construction.

FIGURE 5 is a sectional elevational view as seen at a location corresponding to a line 5—5 of FIGURE 4 with the gate in open position and showing in conventional dot and dash lines the position of the leading end of the gate when released from the supporting ledge.

FIGURE 6 is a vertical transverse sectional view taken through the hopper on a line 6—6 of FIGURE 2.

FIGURE 7 is a fractional transverse sectional view in perspective taken through the frame assembly and showing the relation between the upper and lower frame members with the gate in closed position.

In said drawings the car structure proper is indicated by a center sill 10 and an outwardly spaced side wall 11. Intermediate the center sill 10 and side wall 11 is a

2

load containing hopper as generally indicated at 12. It will be understood that similar hoppers are actually located on opposite sides of the center sill 10 in transversely aligned relation but inasmuch as both such hoppers are of similar construction, the description herein will be confined to only one of such hoppers.

The load containing hopper 12 includes oppositely sloping floors 13 and 14 which meet with inner and outer walls 15 and 16 to form a four-sided hopper. The lower margins of the floors and walls forming the hopper 12 are spaced apart to define a discharge area or opening 17. Surrounding the lower portion of the heretofore described hopper 12 is a frame generally indicated at 18 which includes an upper portion having wall sections 19, 20, 21 and 22 which respectively overlie the lower portions of floors 13 and 14 and the lower portions of inner and outer walls 15 and 16. The wall 21 includes an upper vertically disposed portion 23 and an inwardly and downwardly inclined portion 24.

The lower portion of the frame 18, which in effect constitutes a chutelike extension of the upper portion as defined by walls 19 to 22 inclusive, includes depending walls 25, 26, 27 and 28 which together form a four-sided enclosure for directing the flow of lading from the load containing hopper 12 in a downward direction. The upper edges of the walls 25, 27 and 28 meet with the undersurfaces of the downwardly sloping walls 19, 21 and 22 and are welded thereto as indicated at 25a, 27a and 28a, respectively. The wall 26, FIGURE 5, preferably consists of a plate bent to channel shape with the web portion disposed at a downwardly inwardly sloping angle and its upper flange 29 spaced from the lower margin of the upper wall 20 to provide a slotted opening 30 in the frame 18. The lower flange 31 extends horizontally rearwardly to reinforce the wall 26.

Extending through the slotted opening 30 of the frame 18 is a sliding gate 34. The gate 34 is flared upwardly at the trailing end 34' to present an inclined end wall 35 and is provided at each side with upwardly and outwardly inclined side walls 36—36. The side walls 36—36, which may be formed of plates welded at 37 to the main body of the gate 34, are preferably disposed to be parallel to and immediately adjacent to the respective overlying wall 22 and portion 24 of wall 21.

The lower portion of upper sloping end wall 20 is reinforced by an angle-shaped member 38 which is applied with one wall 39 in contact with the undersurface 40 of wall 20 and having the adjacent wall 41 extending outwardly to form a shield above the end wall 35 of the gate 34 when closed. The member 38 is secured to the wall 20 by welding as indicated at 42 and 43. The walls 20 and 39 are notched at each end to accommodate the side flanges 36—36 of the gate 34.

At the end of the discharge opening 17 remote from the slotted opening 30 of the frame 18 a shelf 44 extends continuously between the depending walls 27 and 28 of the frame 18 and forms a support for the leading end 45 of the gate 34 when the latter is in closed position.

The trailing end 34' of the gate 34 in its open position is supported on rails 46—46 which extend lengthwise in the general direction of opening movement of the gate 34 for an appreciable distance beyond the adjacent end of the frame 18. The rails 46—46 are interconnected by an angle-shaped member 46'. The rails 46—46 are secured to and extend from the side walls 27 and 28 of the frame 18. The trailing end 34' of the gate 34 is supported by brackets 47 which underlie the gate 34 when it is in closed position. The gate 34 when in closed position is thus only supported adjacent each end and the weight of the gate 34 and lading operates to make tight sealing

contact between the leading end 45 of the gate and its underlying shelf 44.

Intermediate the leading and trailing ends 45 and 34' of the gate 34 there are provided brackets 48—48 which function as supports for the gate 34 when its leading end 45 is released from its supporting shelf 44 as indicated by conventional dot and dash lines in FIGURE 5. The bearing surfaces 49 of brackets 48 are spaced slightly below the undersurface 50 of the gate 34 when the latter is in closed position thus allowing for a slight downward movement of the gate 34 at its leading end 45 upon withdrawal from the shelf 44. An inclined approach 51 to each surface 49 is provided to ease the gate 34 into position above the brackets 48 and in like manner inclined surfaces 52—52 are provided at the respective ends of the shelf 44 to ease the gate into position on the upper surface 44' of the shelf 44. It will be understood that the function of the guiding surfaces 51 and 52 is to lift the gate 34 during its transition from open to closed position.

For the purpose of confining the flow of lading toward its ultimate destination a flexible extension chute 53 is provided as indicated by conventional dot and dash lines in FIGURE 2. The chute 53 is provided with a bordering frame 54 of angle shape including a laterally extending flange 55 for receiving and holding the extension chute 53 in place. Grooves 56 are provided in two adjacent sides 26 and 27 of the frame 18 in which the flange 55 is inserted and flanges 57 are provided on the other two adjacent sides 25 and 28 of the frame 18 against which the flange 55 is held in place by clamps 58.

The operating mechanism for moving the gate 34 includes a rotatable shaft 59 journaled in bearings 60 which in turn are carried by the rails 46 which are secured to and extend from the side walls 27 and 28 of the frame 18. The shaft 59 projects beyond the bearings 60 and toothed pinions 61—61 are non-rotatably mounted on the respective projecting ends. The shaft 59 is preferably of non-circular form. In order to provide circular-shaped journals within the bearings 60 and pinions 61 are each formed with a circularly-shaped journal portion 62 for seating in the bearings 60. Cooperating with the teeth of the pinions 61 are toothed racks 63 and 64 which are pivotally connected with the gate 34 adjacent the trailing end 34' thereof. For effecting a connection between the gate 34 and the racks 63 and 64 a round rod 65 is welded to the trailing end 34' of the gate 34 through the medium of brackets 66 with extensions projecting beyond the sides of the gate 34 to present trunnions 67 constituting the pivots connecting with the racks 63 and 64.

As will be noted by reference to FIGURE 6, the toothed racks 63 and 64 are located outwardly of and on opposite sides of the walls 28 and 27 of the frame 18. Each rack includes a body section of generally inverted T-shape having a horizontally extending body portion 68 carrying a series of teeth 69 on the underside thereof and reinforced by an upstanding flange 70. The racks 63 and 64, as will be understood, are movable with the gate 34 upon rotation of the shaft 59.

Supporting and guiding means are provided to prevent vertical and lateral displacement of the floating portions of the racks 63 and 64. The supporting means for rack 63 include a plurality of shelves 71 extending outwardly from the frame 18 and welded to the side wall 28 at 72. The guiding means includes brackets 73 disposed above the rack 63. The brackets 73 are welded to the wall 22 and extend outwardly therefrom. They have a channel portion 73a to embrace the flange 70 of the rack 63. The rack 64 on the side of the frame 18 opposite to the rack 63 is similarly supported by shelves 74 which extend from the wall 27 and are welded thereto at 75. The guiding means for rack 64 include brackets 76 which are disposed above the rack 64 and have a channel portion 76a to embrace the flange 70. The brackets 76 are welded to wall 27 at 76b.

It will be noted that the racks 63 and 64 are located immediately adjacent the side walls 28 and 27 of the frame 18 and are guided thereby against inward lateral movement. The brackets 73 and 76 prevent outward, inward and upward displacement of the racks 63 and 64. It will be observed that although the racks 63 and 64 are restricted to a generally horizontal straight line path of movement there is, by reason of the pivotal attachment provided by the rod 65 between them and the gate 34, freedom for the gate 34 to adjust itself to a different path of movement as it pivots around the trunnions 67. The provision for allowing the gate 34 to move along a path of movement out of parallel with the path of movement of the racks is of importance in a construction where the angular relation of the gate 34 to the support provided by the shelf 44 and brackets 47 and 48 varies during the transition from closed to open position.

The rack 63 is provided with a shouldered portion 77 located at the end adjacent the pivotal connection with the gate 34 and cooperable therewith is a pivotally mounted dog 78 which is adapted to be swung into the path of movement of the rack 63 when the gate 34 is in closed position. This prevents movement of the rack 63 and the gate 34 in an opening direction. By reason of the interengagement between the teeth 69 of the racks 63 and 64 and pinions 61 on the respective ends of the shaft 59 it will be observed that the gate 34 is securely held in closed position at each side of the frame. The outspread arrangement of the racks 63 and 64 and pinions 61 is conducive to the maintenance of a straight line path of movement of the gate 34 in its transition from open to closed position and vice versa.

The arrangement providing a slight drop in the leading end 45 of the gate 34 upon initiation of the gate opening movement provides for release of the gate surface from the pressure of the lading and is conducive to ease of operation. The absence of continuous supporting rails for the gate 34 within the frame 18 precludes the lodgement of lading in the discharge area and this feature combined with the extension of sloping walls 22 and 24 above the gate 34 assures a clean and complete discharge of lading.

The structure involving an upper section having sloping walls 19, 22 and 24 which nest within a three-sided lower enclosure provided by walls 25, 28 and 27 and having a welded connection therebetween is simple to manufacture and provides exceptional strength and rigidity to the assembly.

What is claimed as new is:

1. In a hopper having an opening for discharge of lading, in combination,
  - (a) a frame bordering the hopper opening including side walls at each side of the opening,
  - (b) a sliding gate movable between the side walls of the frame for controlling discharge of lading and
  - (c) means for moving the gate including:
    - (1) a rotatable shaft journaled in the side walls of the frame and extending beyond said walls to provide end portions projecting outwardly beyond said walls,
    - (2) toothed pinions non-rotatably mounted on the projecting shaft extensions and
    - (3) toothed rack bars juxtaposed to the gate and connected therewith and having engagement with the teeth of the pinions for moving the gate by rotation of the shaft.
2. The invention set forth in claim 1 wherein a swingingly mounted latch element is carried by one of the side walls of the frame for engagement with one of the rack bars to block movement of the gate in an opening direction.
3. The invention set forth in claim 1 wherein guiding means carried by the frame co-operate with the rack bars for confining movement thereof to a rectilinear path.

4. In a hopper having an opening for discharge of lading, in combination,

- (a) a frame bordering the hopper having laterally spaced side walls and longitudinally spaced end walls,
- (b) a sliding gate movable between the side walls for closing the opening and having a portion projecting beyond one of the end walls when in closed position,
- (c) bracket means extending laterally from each side of the projecting end of the gate to lie outwardly of the side walls of the frame,
- (d) a shaft extending transversely to the direction of movement of the gate and having extensions lying outwardly of the side walls of the frame,
- (e) toothed pinions nonrotatably mounted on the shaft extensions and
- (f) toothed rack members extending lengthwise in juxtaposed relation to the gate and lying outwardly of the frame side walls and connected at one end to the laterally extending brackets of the gate,
- (g) said teeth of the rack members being in meshing engagement with the teeth of the pinions for moving the gate by rotation of the shaft.

5. The invention set forth in claim 4 wherein the laterally extending brackets of the gate are in the form of circularly shaped brackets and the rack members are pivotally connected therewith to provide limited up and down

swinging movement of the leading end of the gate in relation to the rack members.

6. The invention set forth in claim 4 wherein the rack members are maintained in spaced relation to axis of the pinions by means of supports located fore and aft of the pinions and wherein

- (a) the brackets on the gate constitute the fore supports and
- (b) shelves extending laterally from the frame side walls to underlie the rack members constitute the aft supports.

7. The invention set forth in claim 4 wherein the rack members include an upstanding wall extending lengthwise in the general direction of movement of the gate and brackets extending from the frame overlie the upstanding wall to maintain said members against upward and lateral movement.
